UNITED STATES PATENT OFFICE.

NEWTON L. BARGER AND JAMES P. DONALDSON, OF AMHERSTDALE, WEST VIRGINIA.

LOADING-MACHINE.

1,307,335.

Specification of Letters Patent. Patented June 24, 1919.

Application filed January 3, 1918. Serial No. 210,186.

To all whom it may concern:

Be it known that we, NEWTON L. BARGER and JAMES P. DONALDSON, citizens of the United States, residing at Amherstdale, in the county of Logan, State of West Virginia, have invented certain new and useful Improvements in Loading-Machines; and we do hereby declare the following to be a full, clear, and exact description of the invention, such as will enable others skilled in the art to which it appertains to make and use the same.

This invention relates to mining machinery and has particular reference to machines for gathering and loading coal in coal mines.

The object of the invention is to provide a machine for practically and rapidly removing coal from a chamber after a mass has been "shot." Heretofore, for cutting and loading a quantity of coal, it has been necessary to manually break the lumps and shovel them into mine cars for removal to the hoisting shaft. By means of my invention, this coal is gathered, and is partly disintegrated in the gathering process, and after being thrown upon a conveyer, is hoisted by the latter into a suitable position for dumping into mine cars.

In carrying out the above invention, we have employed a supporting and operating mechanism which is practically identical with that of a usual form of short wall cutting machine for undercutting the coal and utilizing the same sort of mechanism for progressing the machine into the pile of broken coal, as is employed for moving the cutting machine.

With the above objects in view, and such others relating to the details of construction, as may hereinafter appear, our invention will now be fully set forth and described, reference being had to the accompanying drawings.

In the drawings:

Figure 1 is a plan view of the machine,

Fig. 2 is a side elevation,

Fig. 3 is a longitudinal section there-through,

Fig. 4 is a view of the power plant,

Fig. 5 is a detail perspective view of the conveyer belt,

Fig. 6 is a section on line 6—6 of Fig. 1,

Fig. 7 is a further sectional detail view of the conveyer mechanism, and

Fig. 8 is a section on line 8—8 of Fig. 1.

Referring more particularly to the drawings, 1 represents the base or frame machine, upon whose rear end is raised the casing or housing 2 within which the driving mechanism of the machine is carried. In all of its essential particulars the motive power which is housed within the casing 2 is the same as that which is used upon an undercutting mining machine, and the progress and operation of the machine will be controlled in like manner. Thus, the machine will be provided with the usual system of drums and cables which, with the co-operation of jacks will be manipulated to cause the machine to progress forwardly or sidewise through the coal pile. Since this mechanism forms no part of the present invention, it is not shown, since its disclosure on the drawings would merely confuse the present invention.

The loading mechanism of this invention, consists, essentially, of an elevating conveyer 3, a forward gathering roller 4, a set of side gathering rollers 5 and an intermediate roller 6, the rollers 4, 5, and 6 co-operating to take the coal from the pile and deposit it on the conveyer by means of which it will be carried to the mine cars for transportation.

The conveyer 3 is formed of one continuous flexible belt having the side chains 7 which operate over sprockets 8 carried by shafts 9. Said shafts 9 which have their bearings in the sides 10 of the framework, divide the belt 3 into three flights, a horizontal flight *a*, an intermediate flight *b* and a delivery flight *c*. The flight *a* is horizontal, and receives the coal which, is delivered by the rollers 4, 5 and 6, whence it is carried onto the flight *b* and finally is delivered from the flight *c*, the buckets 11 which are carried by the belt 3 insuring the continuous progress of the coal with the belt.

The rollers 4, 5 and 6 inclose one side and the free end of the flight *a* and the opposite side of the flight is inclosed by a comparatively high sideboard or guard plate 12 which continues the sideboard 10 upon the corresponding side. The roller 4 is mounted upon a shaft 13 extending across the front end of the frame structure, and carries upon

its periphery a number of spiral series of cutter blades or teeth 14. The blades or teeth 14 serve to lift the coal, and exert a partial disintegrating action upon the larger lumps, where the latter prove too heavy to be conveniently manipulated by the roller. Also, the spirally arranged teeth are so mounted that the coal which is carried over the roller 4 is thrown toward the guard plate 12 so that its tendency is to hug the latter as the belt 3 progresses toward the upper flights. The roller 5 extends practically throughout the length of the flight a, and carries an axial shaft 15 which is fixed within the heads of the roller, the latter being preferably formed as a hollow metal drum. Formed in the periphery of the drum at suitable intervals is a plurality of bearing grooves 16 within which are received the bearing rings 17 which form part of brackets 18 extended from the side of the main frame structure. Preferably, ball bearings 19 are interposed between the rings 17 and the grooves 16 in order to avoid as far as possible the bearing frictions. The roller 5 also has the series of spirally arranged teeth 14, which attack the coal pile so as to carry the coal onto the conveyer belt 3 and then to move it toward the forward end of the flight a in accordance with the progress of the conveyer. At the outer end of the drum 5 the shaft 15 is extended a distance which approximates the diameter of the roller 4, and upon the extended end of the shaft there is mounted the short roller 6 which is also provided with the spiral series of teeth 14, so that the coal which backs up is thrown over its periphery and toward the angle between the rollers 4 and 5 and also upon the roller 4. Between the rollers 5 and 6 there is mounted in any suitable manner the spur gear 20 which meshes loosely with a second spur gear 21 mounted upon the end of the shaft 13 of the roller 4, the shaft of the roller 5 thereby driving both the drums 4 and 6.

The opposite end of the shaft 15 is provided with a bevel gear 22 which, in turn, stands in mesh with a bevel gear 23 carried upon a vertical stub shaft 24. The vertical shaft 24 is mounted in a bearing bracket 25 extended from the side of the main frame, and also carries the sprocket over which a sprocket chain 26 operates. The opposite end of the sprocket chain then passes over a sprocket wheel 27 which is mounted upon a stub shaft 28 within the housing 2, the latter, in turn, through the bevel gears 29 and 30 being geared to the power shaft of the motor 31. In this manner, the motive power for the rollers 4, 5 and 6 is furnished through a single driving element.

As a means to aid the conveyer belt 3, in its several flights, to support the load upon its upper run, we place the supporting

plates 32 between the runs at the different flights, the plates 32 being carried by the side elements of the frame structure, and extending practically throughout the length of the several flights. The frame elements 70 which support the flight c form a unit aside from the main frame structure, to which the unit is hinged on the axis of the shaft 9 between the flights b and c, and the delivery end of the adjustable flight c is supported 75 by means of a jack 33 of ordinary construction which is interposed between the lower side of the movable unit and the base 1. In order to hold the lower run of the belt 3 into the obtuse angle between the 80 flights b and c, we place the guard plates 34 which overlie the edges of the belt and the chains 7 upon which the belt is mounted. At the delivery end of the flight c, we place a chute 35 which will break the fall of the 85 coal from the end of the flight and aid in delivering the coal into the mine cars. The belt 3 is driven from a worm 36 which is mounted upon the shaft 37 of the motor 31, said shaft 37 extending through the forward 90 end of the casing 2, and carrying upon its extended end the worm 36. Meshing with the worm 36 is a worm gear 38 mounted upon a counter-shaft 39 extending across the frame structure. The counter-shaft 39 also 95 carries a sprocket wheel 40 upon its outer end upon which a sprocket chain 41 operates. The sprocket chain 41 also passes over a sprocket 42 carried upon the end of the shaft 9 between the flights b and c, the necessary 100 power for the operation of the belt 3 being in this manner communicated from the motor 31.

In the operation of the above described machine, it is mounted in a gallery or chamber, after a mass of coal has been shot, in the same relation to the pile of coal that the cutting machine had for undercutting the face from which the pile was shot. Also, as heretofore stated, the machine is anchored to 105 jacks by means of cables whose opposite ends are wound upon the machine frame, in the same manner in which a cutting machine is installed, for progressing it with relation to the face. Then, the operating mechanism is 110 started to drive the rollers 4, 5 and 6 and to drive the conveyer belt 3. The action of the rollers 4, 5 and 6 is to lift the coal from the pile against which the machine is driven, either longitudinally or transversely, and deposit it upon the lower end of the conveyer 115 belt 3. If the coal is not sufficiently broken, the teeth upon the rollers sufficiently disintegrate the coal as the rollers operate thereagainst, to size the coal for lifting onto the 120 belt. It will be noted that the rollers throw the coal longitudinally of the belt and also toward the guard plate opposite the roller 5, so that a proper progression of the coal after it has struck upon the conveyer 3 is in- 125 130

sured. The conveyer belt 3 carries the coal to the upper end of the movable flight, and chutes into the coal cars in an obvious manner.

5 An important feature of the invention lies in the particular arrangement of the rollers 6 and 4 with respect to each other. It will be noted that, since the roller 6 extends across the end of the roller 4 and is 10 mounted to rotate upwardly and inwardly toward the roller 4, coal contacted by the roller 6 and by its teeth will be carried by the roller 6 not only into the angle between the rollers 4 and 5, but also onto the roller 4 15 as well, from which roller the coal is thrown upon the conveyer and also urged toward the guard plate 12. Thus, not only is there provision for action upon a greater quantity of coal, through the added area of coal end 20 gaging surface represented by the roller 6, but this roller 6 also prevents the passage of lumps of coal into engagement with the end of the roller 4, which might interfere with the operation of this roller.

25 It will be apparent from the foregoing description that there has been provided a very practical machine for taking coal in the form in which it is left after a shooting and placing it directly into the mine cars, 30 without the necessity of employing manual labor, in accordance with the method which has been heretofore in use.

After a vein has been undercut and shot, the cutting machine may be employed in another gallery or chamber, and the loading 35 machine may be substituted therefor, to transfer the coal which has been brought down into cars.

While we have shown and described a preferred embodiment of our invention, it will 40 be understood that various changes and modifications of the structure may be resorted to for differing condition of use without departing in any manner from the scope 45 of the appended claims. While we have

shown no specific mounting for the inner end of the roller 4, such mounting may take the form of a ball bearing such as shown in connection with the roller 5.

What we claim as our invention is:— 50

1. A loading machine, comprising in combination, a framework, a conveyer mechanism mounted upon the framework in elevating flights, and a series of rollers mounted around the receiving end of the conveyer mechanism to deliver material from a pile against which said rollers are brought onto said conveyer, one of said rollers extending across an end of another of said rollers and being arranged to rotate upwardly and inwardly toward said other roller. 55

2. A loading machine, comprising in combination, a framework, a conveyer mechanism arranged upon the framework in elevating flights, rollers arranged around the 60 forward and one side edge of the receiving end of the conveyer mechanism, a guard plate extending along the other side edge, and means upon the rollers for directing material lifted by the latter onto the conveyer 65 toward said guard plate.

3. A loading machine, comprising in combination, a framework, a conveyer mechanism arranged upon the framework in elevating flights, rollers arranged around the 70 forward and one side edge of the receiving end of the conveyer mechanism, a guard plate extending along the other side edge, and spiral series of teeth arranged around the 75 rollers so as to direct the material lifted 80 by the rollers toward said guard plate and in the direction of operation of the conveyer mechanism.

In testimony whereof, we affix our signatures in the presence of two witnesses.
